WINDOW STRUCTURE

Frank G. Ludwig, Lockport, Ill.

Application February 23, 1937, Serial No. 126,966

5 Claims. (Cl. 20—56.5)

This invention relates to window structures and more especially to such structures as apply to windows of motor vehicles.

As is well known, by the present type of window construction for motor vehicles frosting occurs on the inner side of the glass during cold weather, and it is very difficult to prevent this formation because of the unavoidable humidity in the passenger compartment which condenses on the inner side of the glass when the outer side of the glass is cold.

It is to overcome this that my present invention has been conceived and developed and consists essentially in the formation of the window panes into a unit having an inner pane and an outer pane separated by an evacuated space so that the transfer of heat or temperature from the inner to the outer side will not occur and frosting of the inner pane will be prevented.

It is therefore an object of my invention to provide a simple practical and inexpensive article of the character described.

Another object is to provide a window glass construction adapted to prevent frosting of windows in cold weather.

Another object is to provide a window glass having improved heat and cold resisting characteristics.

Other objects and advantages will appear and be brought out more fully in the following specification, reference being had to the accompanying drawing, wherein:

Fig. 1 is a partial view of a motor vehicle body having windows constructed according to my invention;

Fig. 2 is an enlarged fragmentary section taken along the line 2—2 of Fig. 1;

Fig. 3 is a perspective view of a portion of the pane of Figs. 1 and 2;

Fig. 4 is a fragmentary view of a building wall showing the windows constructed according to my invention;

Fig. 5 is an enlarged section taken along the line 5—5 of Fig. 4;

Fig. 6 is a cross-section of a window construction employing a modification of my invention; and

Fig. 7 is a similar view illustrating a further modification.

Referring more particularly to the drawing and especially Figs. 1-3, I show a fragmentary portion of a motor vehicle body 10 having a front windshield frame 11 provided with a windshield glass 12 and having a side window 13. The window 12 comprises an inner pane 14, and an outer

pane 15, separated by an evacuated space 16. The inner pane 14 comprises a sheet of glass 17 having a layer of celluloid 18 suitably adhered thereto and preferably on the side presented to the evacuated space 16. The celluloid 18 is adapted to maintain the glass 17 shatter-resistant or shatterproof in case of injury or accidental fracturing of the glass. Similarly, the outer pane 15 comprises a glass sheet 19, the inner surface of which has similarly secured to it a celluloid sheet 20. The edges of the panes 14 and 15 are separated by a suitable spacing strip 21, and if desired the glass may be fused together forming the fused edge 22.

It may be found desirable in practice to provide panes 14 and 15 each with two layers of glass, 17 and 17a and 19 and 19a, and provide the celluloid with both its surfaces cemented to the glass. By this arrangement greater strength is provided and there is reduced tendency of the celluloid to become waved or wrinkled or spotted due to extreme changes of temperature. The double pane construction of Fig. 7 may be provided with the fused edge of Fig. 2 as illustrated in Figs. 4 and 5, wherein windows 23 are suitably set in frames 24.

From the foregoing description it will be apparent that the evacuated space 16 provided between the panes 14 and 15 will permit the outer pane 15 to be kept at a temperature very materially lower than that of the inner pane 14, such that the moisture of the air in the passenger compartment of the motor vehicle will not condense upon the inner pane, which under these circumstances will not ordinarily become cold enough to condense this moisture into frost formation.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A window structure as described, comprising spaced panes fused together at the edges, said space being evacuated, and said panes having inner surfaces thereof provided with shatterproof material.

2. A window structure as described, comprising

spaced panes fused together at the edges, said space being evacuated, and said panes having shatterproof material secured on the inner surfaces thereof.

- 5 3. A window structure as described, comprising spaced panes fused together at the edge portions thereof, said space being evacuated, and said panes each comprising a pair of panes having a layer of shatterproof material therebetween.
- 10 4. A window structure as described, comprising spaced panes fused together at the edge portions

thereof, said space being evacuated, and said panes each comprising a pair of panes secured to the opposite sides of a sheet of shatterproof material.

- 5 5. A window structure as described, comprising spaced panes fused together at the edge portions thereof, said space being evacuated, and said panes each comprising a unit having a layer of shatterproof material embedded in the central portion thereof.

10 FRANK G. LUDWIG.
